WINDOW VENTILATOR

Rodolphe Amiot, San Francisco, Calif.

Application June 12, 1943, Serial No. 490,615

6 Claims. (Cl. 98—99.1)

This invention relates to a window ventilator, and has for several of its objects the provision of an improved ventilator that is easily and quickly installed in an ordinary window opening without defacing the window frame or sash, and which ventilator may be quickly removed from such opening, and when in operative position in the opening is more efficient for regulating the ventilation than heretofore.

Another object is the provision of a window ventilator for use in a window opening that will freely admit air to the room having said opening free from rain, snow, sleet, etc., even though accompanied by a strong, gusty and changeable wind, and which ventilator is provided with means for regulating the volume of air admitted therethrough and for controlling the point of said admission to that portion where there is no likelihood of rain, snow or sleet entering the room under even the most abnormal and unusual conditions.

Other objects and advantages will appear in the drawing and description, and some of these, while apparently of minor significance, are quite important, such as means of insuring a rattle-proof installation and one in which the parts that are adjustable will remain fixed in adjusted position automatically. Economy of manufacture and simplicity are further features, together with provision for admitting air while shutting out insects and considerable quantities of dirt.

In the drawing:

Fig. 1 is a perspective view of a ventilator illustrative of the invention in which a portion is broken away and in section to show certain structure. Part of the window frame and sash are also indicated, these elements being conventional.

Fig. 2 is a vertical sectional view taken transversely through a ventilator such as is shown in Fig. 1 except that the closure for the ventilator opening is positioned in Fig. 2 for shutting out more air than the closure in Fig. 1. In dot-dash line in Fig. 2 is indicated the position of the closure when it is fully open.

Fig. 3 is a fragmentary elevational view, partly broken away and in section, of the left hand end of the ventilator of Fig. 1.

Fig. 4 is a fragmentary elevational view of a portion of the closure for the ventilator.

Fig. 5 is a perspective view of a pair of wedge strips used at opposite ends of the ventilator for securely holding the ventilator in the window opening.

In detail, the main body of the ventilator is preferably of rigid, self-sustaining material fabricated to produce an awning-like shape in which there is a horizontally elongated flat transversely slanted top 1 and a triangular end plate 2 at each opposite end. The edges of each end plate illustrated in the drawing follow the contour

of a right angle triangle with the edge that corresponds to the hypotenuse being against the top 1 at an angle of about 45° relative to horizontal, while one of the other edges is vertical and the third is horizontal.

On each end plate 2 is a pair of spaced parallel vertical strips 3 corresponding in their spacing to that which is between strips 5 that slidably retain sash 6 therebetween at opposite vertical edges of the latter, while along the upper edge of top 1 is a horizontal upwardly projecting strip 7 secured to said top.

The space between each pair of vertical strips 3 is adapted to slidably support a vertically elongated wedge member 8 (Fig. 5) therein, while a similar wedge member 9 is adapted to be positioned within the space between strips 5 (Fig. 3). When the inclined sides of each pair of wedge members 8, 9 are together their oppositely outwardly facing sides that respectively engage the ventilator and the window frame are parallel. The thicker end of each wedge 8 may partially extend into the space between the strips 3 at each end of the ventilator, while the thicker end of each wedge 9 may extend into the space between the pairs of strips 5 respectively, said pairs of wedge members being insertable into said spaces from above the ventilator when the lower sash is raised to its maximum height. Thus the wedge members 8, 9 at each end of the ventilator will hold the latter tightly in position in the window opening and will also close off any cracks that might exist between the ends of the ventilator and the sides of the window frame. If desired, the adjacent sides of each pair of wedge members 8, 9 may be of tongue and groove contour (Fig. 5) so as to insure a tight seal at their adjacent sides.

In each of the end plates 2 and between the members 3 is a vertically elongated slot 10 through which the end of any suitable instrument, such as a screw driver, pick, or the like, may be inserted for engagement with a plate 11 (Fig. 5) on member 9 for lifting said member to remove it, so that the two members 8, 9 at each end of the ventilator may be removed for removal of the ventilator. Plate 11 may be serrated on its face that is over opening 10 to facilitate engagement with such lifting instrument, and each plate 11 may be of metal, secured in member 9 with its outer side flush with the outer side of said member. The wedge members 8, 9 may be of wood treated to be water repellent, or they may be of any other suitable material.

The wedge members also function to hold the ventilator in the window opening in such a position that the lower sash 6 will engage the top 1 adjacent strip 7 and in overlapping relation to the latter, thereby preventing ingress of moisture to the room over the upper edge of top 1.

Inside the body of the ventilator and slightly

spaced above the lower edge of top 1 and the lower sides of end plates 2 is a horizontally disposed, centrally open rectangular frame.

This frame may comprise a pair of frames 15, 16 (Fig. 2), with frame 15 positioned over frame 16 and with the inwardly facing edges of frame 15 projecting slightly inwardly relative to the corresponding edges of upper frame 15 whereby an upwardly facing ledge 17 is provided.

The ends of frames 15, 16 adjacent end plates 2 are secured thereto, and the sides of the frames adjacent the top 1 are secured to the latter. The upper inner corners of the end members 18 of frame 16 are rabbeted (Fig. 3) whereby the adjacent ends 19 of frame 15 will cooperate with the said rabbeted corners to provide opposed grooves 20 at each end of the respective frames and at each end of the ventilator along the lower edge of the latter.

Below the frames and between the lower right angle corners of ends 2 is a bar 21 (Fig. 2). This bar may rest on the sill 22 of the window frame when the ventilator is in the window, and such sill is ordinarily formed with a downward offset (Fig. 1) that will be overlapped by a side of bar 21, thus preventing any leakage past bar 21 and into the room.

Below frame 16 and secured thereto by half rounds 22 is a screen 23 that extends across the frame openings. The half rounds are secured to frame 16 in the usual manner, as by brads or nails.

A closure for the frame openings is provided for in the form of a rectangular plate 24 that is adapted to extend at its edges over the ledge 17 provided by the inwardly projecting frame 16. Thus the plate 24 is spaced by frame 16 above screen 23, and when the plate is resting along all four of its edges on ledge 17 the frame openings will be tightly closed.

This plate 24 carries a pair of oppositely outwardly projecting pins 25 (Figs. 2, 4) at the ends of its edge that is adapted to lie adjacent lower edge of top 1 when the plate is in frame closing position. These pins extend into slots 20 and are slideable between the sides of said slots. Along the opposite edge of plate 21 is a lifting handle 26 (Fig. 2).

Over the side of frame 15 that is above bar 21 is a horizontal vertically disposed strip 27, said strip extending from end to end of the ventilator.

Along the opposed sides of the ends 2 of the ventilator and above the ends of strip 27 are vertically extending strips 28. The lower ends of strips 28 are spaced from the strip 27 so as to permit the closure plate 24 to be withdrawn from frame closing position over the strip 27, while the pins 25 will slide in grooves 20 and will hold the edge of said plate opposite handle 26 adjacent the ledge 17.

The strips 28 carry leaf springs 29 that slidably engage the upper side of plate 24 at its ends adjacent grooves 20 to yieldably hold the pins 25 against the lower side of each groove 20 and to also hold said plate against the strip 27. Thus the plate is yieldably held at all times from rattling, even when plate 24 closes the frame opening or when it is in fully open position indicated in dot-dash line at 30 (Fig. 2).

When the plate 24 is moved to position 30 it may be completely withdrawn from the ventilator, if desired, by moving it in the plane thereof so that pins 25 will pass out of frame 15 through slots 31 (Fig. 2) in the ends of said frame.

Also slots 32 in members 28 (Fig. 3) will pass said pins.

In operation when the ventilator is in the window, the desired amount of air can be admitted by adjusting the closure plate 24, and it is particularly pertinent to note that the greater the amount of air that is admitted, the more such air is deflected upwardly by plate 24, since said plate will move to a position substantially parallel with top 1 when this plate is moved to fully open position.

Air on the sides of buildings tends to move directly upwardly along said sides, hence the outwardly projecting top 1 will deflect such air into the room and will thereby tend to keep room air in circulation, whereas if the ventilator did not have its opening directed downwardly, and if it did not project outwardly of the wall of the building, no such result would be possible.

It is obvious, of course, that practically no moisture may enter the room through the ventilator during a rain, but should the storm be one of particular violence and lack of direction, the full line position of the closure plate 24 as shown in Fig. 2, will keep out the rain and will at the same time provide for ventilation.

The screen 23 also keeps out undesirable insects, etc., and in particularly dusty localities this screen may be of cloth or of relatively fine mesh.

The springs 29 automatically hold the closure plate 24 in its adjusted position and also prevents any rattling of the plate in windy weather. All other parts are tightly held, so there is no rattling of elements in the ventilator or between parts of the ventilator and the window frame.

Having described my invention, I claim:

1. A ventilator comprising a horizontally elongated transversely inclined sheet adapted to extend between the jambs of a window frame at its upper horizontal edge with its lower horizontal edge spaced outwardly of the sill of such frame and about level with the latter, and means at the ends of said sheet for detachably securing it to such frame and in the aforesaid position relative thereto including opposed end walls at the opposite ends of said sheet respectively and secured thereto; a closure plate adapted to extend from about the lower edge of said sheet to such sill and between said end walls when said sheet in the aforesaid position is in a window frame; means including strips on said end walls forming horizontally extending slots and members on the ends of said closure adjacent its edge that is nearest the lower edge of said sheet extending into said slots for supporting said plate for sliding of the latter to different distances from said sheet and into the frame opening when the sheet is secured in said frame; guide means connected with said end walls slidably engaging the said closure plate at its ends during its sliding movement in direction away from said sheet for supporting said plate in various degrees of inclination from horizontal to opposed parallel relation to said sheet according to the distance said plate is moved away from the lower edge of said sheet said guide means including elements adjacent said end walls and rigid therewith forming a pair of opposed slots above the ends of said horizontally extending slots that are nearest such frame and through which opposed slots said closure is adapted to extend at its end edges.

2. A ventilator comprising a horizontally elongated transversely inclined sheet adapted to ex-

tend between the jambs of a window frame at its upper horizontal edge with its lower horizontal edge spaced outwardly of the sill of such frame and about level with the latter, and means at the ends of said sheet for detachably securing it to such frame and in the aforesaid position relative thereto including opposed end walls at the opposite ends of said sheet respectively and secured thereto; a closure plate adapted to extend from about the lower edge of said sheet to such sill and between said end walls when said sheet in the aforesaid position is in a window frame; means connecting said plate with said end walls for sliding of the plate to different distances from said sheet and into the frame opening when the sheet is secured in said frame; said last mentioned means comprising a pair of oppositely outwardly extending projections at opposite ends of said plate providing opposite sides of channels between which said ends are slidably means on said plate extending into said channels and a pair of elements spaced above said channels and adjacent such frame opening forming supports for holding said plate in inclined position when said last mentioned means is in said channels.

3. A ventilator comprising a pair of vertical flat opposed end members of similar shape and size; said members being positioned with one of their corresponding edges similarly inclined and with the remaining two edges of each extending horizontal and vertical providing a substantially right angle corner at their junctures respectively; an elongated transversely inclined rectangular sheet secured at its end edges to said end members along the said inclined edges of the latter; a pair of parallel horizontally extending strips secured to said members adjacent the said horizontal edges of the latter; an elongated rectangular plate adapted to be supported at its ends on said strips for movement generally longitudinally of the latter from between said end members in direction generally away from said sheet; and means for removably securing said end members alongside the jambs of a window frame adjacent the sill of such frame; a cross bar parallel with said sheet connecting the said right angle corners of said members and terminating at its ends adjacent one of the corresponding ends of said strips, the upper side of said cross bar being elevated above the upper sides of said strips and being adapted to slidably support said closure plate in inclined position during said movement of the latter; means carried by said end members for holding said plate in such inclined position at certain points in its path during such movement.

4. A ventilator comprising a pair of vertical flat opposed end members of similar shape and size; said members being positioned with one of their corresponding edges similarly inclined and with the remaining two edges of each extending horizontal and vertical providing a substantially right angle corner at their junctures respectively; an elongated transversely inclined rectangular sheet secured at its end edges to said end members along the said inclined edges of the latter; a pair of parallel horizontally extending strips secured to said members adjacent the said horizontal edges of the latter; an elongated rectangular plate adapted to be supported at its ends on said strips for movement generally longitudinally of the latter from between said end members in

direction generally away from said sheet; and means for removably securing said end members alongside the jambs of a window frame adjacent the sill of such frame; said last mentioned means comprising a pair of vertically elongated relatively movable wedge members adapted to be positioned between said end members and the jambs of such frame; said end members being formed with outwardly opening vertical channels on their outwardly facing sides along their said vertical edges for holding said wedge members therein.

5. A ventilator comprising a pair of vertical flat opposed end members of similar shape and size; said members being positioned with one of their corresponding edges similarly inclined and with the remaining two edges of each extending horizontal and vertical providing a substantially right angle corner at their junctures respectively; 15 an elongated transversely inclined rectangular sheet secured at its end edges to said end members along the said inclined edges of the latter; a pair of parallel horizontally extending strips secured to said members adjacent the said horizontal edges of the latter; an elongated rectangular plate adapted to be supported at its ends on said strips for movement generally longitudinally of the latter from between said end members in direction generally away from said sheet; and 20 means for removably securing said end members alongside the jambs of a window frame adjacent the sill of such frame; said last mentioned means comprising a pair of vertically elongated relatively movable wedge members adapted to be positioned between said end members and the jambs of such frame; said end members being formed with outwardly opening vertical channels on their outwardly facing sides along their said vertical edges for holding said wedge members therein: 25

30 said end members each being formed with an opening communicating with the bottom of each such channel for insertion of a pointed wedge

35 loosening instrument into engagement with one of said wedge members from the inner opposed

40 sides of said end members.

6. A ventilator comprising a pair of vertical flat opposed end members of similar shape and size; said members being positioned with one of their corresponding edges similarly inclined and with the remaining two edges of each extending horizontal and vertical providing a substantially right angle corner at their junctures respectively; an elongated transversely inclined rectangular sheet secured at its end edges to said end members along the said inclined edges of the latter: 50 a pair of parallel horizontally extending strips secured to said members adjacent the said horizontal edges of the latter; an elongated rectangular plate adapted to be supported at its ends on said strips for movement generally longitudinally of the latter from between said end members in direction generally away from said sheet; and means for removably securing said end members alongside the jambs of a window frame adjacent the sill of such frame; a pair of leaf springs yieldably engaging the upper sides of said closure plate adjacent its ends for urging said plate downwardly at all times toward said strips, projections 55 on the ends of said closure plate slidable on said strips and means securing said springs to said end members.

RODOLPHE AMIOT.
